C. F. GIERKE

Des. 165,520

BROOCH OR SIMILAR ARTICLE

Filed July 12, 1951

FIG. 1.

FIG. 2.

INVENTOR,
CARL F. GIERKE,
By Herbert A. Minturn,
ATTORNEY.

UNITED STATES PATENT OFFICE

165,520

BROOCH OR SIMILAR ARTICLE

Carl F. Gierke, Indianapolis, Ind., assignor to Grand Chapter of Indiana, Order Eastern Star,
Indianapolis, Ind., a corporation of Indiana

Application July 12, 1951, Serial No. 15,849

Term of patent 14 years

(Cl. D29—2)

To all whom it may concern:

Be it known that I, Carl F. Gierke, a citizen of the United States of America, residing at Indianapolis, Indiana, and whose postal address is 209 Massachusetts Avenue, Indianapolis, Indiana, have invented a new, original, and ornamental Design for a Brooch or Similar Article, of which the following is a specification, reference being had to the accompanying drawing, forming a part thereof.

In the drawing:

Fig. 1 is a front elevational view of a brooch or similar article embodying my new design; and
Fig. 2 is a side elevational view thereof.

I claim:

The ornamental design for a brooch or similar article, substantially as shown.

CARL F. GIERKE.
